NECKTIE HOLDER

Charles Silverman, Providence, R. I.

Application October 9, 1939, Serial No. 298,531

2 Claims. (Cl. 24—49)

My invention relates to improvements in necktie holders or clasps for positively holding each edge of a fore-in-hand necktie in flat position on the shirt of a wearer.

I am aware that others have provided pivotal members for engaging both the inner and outer edges of the necktie holder pivotally mounted on a suitable pivot in rear of the shirt edge so that any spring pressure exerted against the pivot is pivotally transmitted to the necktie through the pivot point of the pivotal member alone.

Necktie holders of the general type to which my invention relates have comprised in the prior art, a bar, whether ornamental or otherwise, adapted to overlie the necktie and underlying shirt edge and an integral outer end bent rearwardly and then inwardly to provide a rear portion under a portion of the rear face of said bar in spaced relationship thereto to underlie said shirt edge having the aforementioned pivotal member pivotally mounted thereon. As the material of the necktie holder has been somewhat resilient, it is obvious that the rear portion of said necktie holder may pivot on one end of the rearwardly extending portion relative to the front bar portion, which movement is transmitted at the point of pivot to each inner and outer gripping portion of said pivotal member pivotally mounted thereon. Inasmuch as the pivotal member itself pivots, it is obvious that the force of the resilient pivotal movement of the rearwardly extending portion of the necktie holder is broken into two components which tilt relative to each other. With my improved construction, however, I transmit the resilient pivotal movement of the rear bar portion through a single nip provided by a flat element secured to said rear bar portion extending resiliently inwardly and forwardly to abut the rear surface of the shirt edge adjacent the inner edge of the necktie or in another embodiment of my invention, employing a pivoted clamping member resiliently urged towards the front bar for the same purpose, the whole force of said resilient movement is also transmitted through said flat element gripping the rear surface of said shirt edge adjacent the inner edge of said necktie. To grip the outer edge of the necktie and underlying shirt edge, I provide a separate resilient flat element extending resiliently outwardly and forwardly from the shirt edge underlying portion of said necktie holder to abut the rear surface of said shirt edge adjacent the outer edge of said necktie and shirt edge to provide a re-

silient nip to positively provide independent resilient pressure against the outer edge of the necktie to positively grip through independent resilient means independently resiliently actuated, both the inner and outer edges of the necktie with two separate independent nips. Thus broadly, my invention includes the provision of this separate flat element extending resiliently outwardly and forwardly from a shirt edge underlying portion of the necktie holder to abut the rear surface of said shirt edge adjacent the outer edge of the necktie and shirt edge no matter on what kind of a prior art necktie holder it be employed. It is immaterial how this supplemental flat element to provide the other nip be added to prior art types of necktie holders, or how such prior art types of holders may be modified to achieve this result.

An object of my invention therefore is to transmit the entire resilient movement of the rearwardly extending portion of the necktie holder to the inner nip for resiliently binding the inner edge of the necktie against the front bar, or to employ the entire force of other resilient means employed for this purpose at this nip.

A further object of my invention is to provide a necktie holder having two separate necktie engaging elements which do not relatively pivot during insertion to cause a rumpling of the necktie during its insertion. As the necktie is inserted in the holder, the force of one nip is first presented to the necktie, this nip remaining substantially constant while the necktie is further inserted so that the outer nip may be applied to the necktie without varying the position or strength of the inner nip and similarly a construction in which the outer nip will be initially released and the inner nip independently released without any relative tilting movement during withdrawal of the necktie to prevent its being rumpled during its withdrawing operation.

A further feature of my invention resides in the provision of the outwardly extending flat element being of a greater length than the inwardly extending flat element to somewhat equalize the pressure applied by the two nips inasmuch as the resiliency of the inner nip, in most embodiments, depends on the resiliency of the rearwardly projecting portion of the necktie holder.

Further features of my invention relate to the specific modifications of various prior art structures to achieve these desirable results and the structural features of the various embodiments of necktie holders shown.

These and such other objects of my invention as may hereinafter appear will be best understood from a description of the accompanying drawings which illustrate various embodiments thereof.

In the drawings,

Fig. 1 is a front perspective view of one embodiment of necktie holder constructed in accordance with my invention.

Fig. 2 is a rear perspective view thereof.

Figs. 3, 4 and 5 are side elevational views of the necktie holder shown in Figs. 1 and 2, illustrating the positions it assumes while being placed in position showing the necktie and underlying shirt edge in section, Fig. 3 illustrating the necktie holder about to be attached to grip the necktie against the shirt edge, Fig. 4 illustrating the necktie holder half attached with the inner flat element positively evenly gripping the necktie in even amounts over successive portions of the necktie as it is being attached and Fig. 5 illustrating the necktie holder in completely attached position, the relative positions of the stationary necktie and underlying shirt edge being relatively distorted from a stationary position in the three figures for ease of illustration.

Fig. 6 is a side elevation of another embodiment of my invention showing my necktie holder in the position of the necktie holder shown in Fig. 3 and also showing the necktie and underlying shirt edge in section.

Fig. 7 is a plan view of an additional embodiment of my invention.

Fig. 8 is a side elevation of the embodiment of my invention shown in Fig. 7.

Fig. 9 is a rear elevation of the embodiment of my invention shown in Figs. 7 and 8.

Fig. 10 is a plan view of an additional embodiment of my invention.

Fig. 11 is a side elevation of the embodiment of my invention shown in Fig. 10.

Fig. 12 is a rear elevation of the embodiment of my invention shown in Figs. 10 and 11.

Fig. 13 is a side elevation of an additional embodiment of my invention.

Fig. 14 is a horizontal sectional view taken along the line 14—14 of Fig. 13 of the embodiment shown therein.

Fig. 15 is a perspective view of an additional embodiment of my invention.

Fig. 16 is a plan view of a still further embodiment of my invention of the type having a separate clamping lever pivotally mounted on the rear portion of the necktie holder.

Fig. 17 is a side elevation of the embodiment of my invention shown in Fig. 16, with portions thereof shown in section.

Fig. 18 is a horizontal sectional view taken along the line 18—18 of Fig. 17 of the embodiment of my invention shown in Figs. 16 and 17.

Figs. 19, 20 and 21 are side elevational views of the embodiment of my necktie holder shown in Figs. 16-18, Fig. 19 illustrating the necktie holder about to be attached to grip the necktie against the shirt edge, the pivoted clamping lever being pivoted to open position to permit it to underlie the shirt edge as the front bar portion of the necktie holder is moved over the necktie, Fig. 20 illustrating the necktie half attached with the clamping lever still in open position and Fig. 21 illustrating the necktie holder is completely attached position, the relative positions of the stationary necktie and underlying shirt edge being relatively distorted from a stationary position in the three figures for ease of illustration.

In the drawings, wherein like characters of reference indicate like parts throughout, 10 generally indicates a necktie holder constructed in accordance with my invention.

5 In view of the fact that so many different embodiments are shown, I will apply alphabetical coefficients in reference to the different embodiments, 10^a signifying the embodiment of necktie holder shown in Figs. 1-5, 10^b signifying the embodiment of necktie holder shown in Fig. 6, 10^c signifying the embodiment of necktie holder shown in Figs. 7-9, 10^d signifying the embodiment of necktie holder shown in Figs. 10-12, 10^e signifying the embodiment of necktie holder shown in Figs. 13 and 14, 10^f signifying the embodiment of necktie holder shown in Fig. 15 and 10^g signifying the embodiment of necktie holder shown in Figs. 16-21 and similarly with the various numerals indicating common component parts 10 of the respective embodiments.

My invention relates to necktie holders securing a necktie in flat formation overlying a shirt edge and in the claims I employ the words "inner" and "outer" relative to the outer edge of said shirt edge, both in reference to the respective edges of the necktie and the respective portions of the necktie holder. The respective necktie holders 10^a, 10^b, 10^c, 10^d, 10^e, 10^f and 10^g comprise the bar 12, (and where the respective parts are common to all embodiments I will not employ the distinguishing alphabetical coefficients in the general written description, although they are applied in the drawings), adapted to overlie said necktie 14 and underlying shirt edge 16, said shirt edge 16 having an outer end 18 and said necktie having an outer edge 20 and an inner edge 22. Said bar 12 may comprise a usually flat element normally of relatively narrow width, although it may be widened if desired, unornamented or suitably ornamented if desired. The portion of said bar 12 overlying said necktie 14 and underlying shirt edge 16 is hereinafter referred to as the front bar portion 12. Said front bar portion has an integral outer end 24 bent rearwardly and then inwardly to provide a rear bar portion 26 extending under at least a portion of the rear face of said front bar portion 12 in spaced relationship thereto to underlie said shirt edge 16. While I have shown the portion 24 bent rearwardly substantially at right angles to said front bar portion 12 and said rear bar portion 26 bent inwardly substantially at right angles to said rearwardly projecting portion 24, it is obvious that the respective front and rear portions 12 and 26 may be connected together by any suitable rearwardly extending connecting portion 24, arcuate as in the embodiments shown in Figs. 7-12 and 16-21, or otherwise.

I employ a flat element 28 rigidly secured to said bar rear portion 26 extending resiliently inwardly and forwardly to abut the rear surface of said shirt edge 16 as at 30 adjacent the inner edge 22 of said necktie to provide a positive nip 30 for said necktie and shirt edge substantially at the inner end of the front bar portion 12 as shown in Figs. 5 and 21. In the embodiments shown in Figs. 1-15, the flat element 28 has the rear end 38 thereof rigidly secured to said rear bar portion 26 and it is obvious that with this rigid securing of the flat element 28 to said rear bar portion 26 that the nip 30 will be provided by the resilient pivoting of said rear portion 26 and rigidly connected flat element 28 along the rearwardly extending portion 24 of said

front bar to provide a leverage extending from said bar portion 24 to said nip 30. I am aware that similar constructions have been provided in the prior art. In the embodiment shown in Figs. 16-21, even though said rear end 38^g is pivotally mounted on the rear bar portion 26^g, it is obvious that some resilient pivoting of the flat element 28^g and rear bar portion 26^g will take place along its respective portion 24^g.

In addition, in accordance with my invention, I provide a supplemental flat element 32 extending resiliently outwardly and forwardly from the shirt edge underlying portion of said necktie holder from a point adjacent said rear bar portion 26 to abut the rear surface of said shirt edge 16 adjacent the outer edge 20 of said necktie and the end 18 of said shirt edge to provide a supplemental nip 34 for the outer edge 20 of said necktie and the outer end 18 of said shirt edge between said flat element 32 and front bar portion 12 as shown in Figs. 5 and 21. If desired the ends of said respective flat elements 28 and 32 may be rearwardly bent as at 36 exterior of their respective nips 30 and 34 for ease of attachment of said necktie holder 10 over said necktie and underlying shirt edge and removal therefrom. In most embodiments of my invention shown, the rear end 40 of said flat element 32 is also rigidly secured to said bar rear portion 26 and in certain embodiments the rear ends 38 and 40 of said respective flat elements 28 and 32 are rigidly secured both to each other and to said bar rear portion 26. The flat element 32 is resilient and its resiliency normally extends from the point of jointure of the rear end 40 thereof to said rear bar portion 26 and its respective nip 34. In order that the leverage exerted by said flat portion 32 may be somewhere near equal to the leverage exerted by the resiliency of said flat portion 28 and rear portion 26, the flat portion 32 is preferably made of greater length than the flat portion 28 as in the embodiments of my invention shown in Figs. 1-5, 6, 13 and 14. If desired, as in the embodiment of my invention shown in Figs. 16-21, the flat portion 28^g may comprise the clamping portion of a clamping lever 42 pivotally mounted as at 44 on the inner end of said rear bar portion 26^g urged by the resiliency of the spring 45 to its nip position 30 abutting the rear surface of said shirt edge adjacent the inner edge of said necktie and in this embodiment the second flat element 32^g may be mounted on the clamping lever 42 itself as shown instead of on the rear bar portion 26^g. In the embodiments of my invention shown in Figs. 1-5, 10-12 and 13-15, each of said flat elements 28 and 32 respectively comprises respective arms 28 and 32 of a flat spring element 46 having a rear portion 41 comprising respective rear portions 38 and 40 of said respective flat elements 28 and 32 integrally joined together to form said spring element 46, said rear portion 41 being rigidly secured to said rear bar portion 26, the respective arm 28 thereof thus extending resiliently inwardly and forwardly from and rear portion 41 to abut the rear surface of said shirt edge adjacent the inner edge of said necktie to provide the nip 30 and the respective arm 32 thereof extending resiliently outwardly and forwardly from said rear portion 41 to abut the rear surface of said shirt edge adjacent the outer edge of said necktie and shirt edge. While said rear portion 41 of said flat spring element 46 may be integrally joined to said rear bar portion as in the embodiment of my invention shown in Figs. 7-9, it may be rigidly joined thereto as in the em-

bodiments of my invention shown in Figs. 1-5, 10-12 and 13 and 14 by a metal strap 48 wrapped around said spring element rear portion 41 and bar rear portion 26 to rigidly secure said spring element to said bar rear portion.

In the embodiment of my invention shown in Figs. 1-5, I employ the composite flat spring element 46^a having the flat element or arm 32^a of greater length than the flat element or arm 28^a thereof for the purpose previously described, and having the rear portion 41^a thereof rigidly secured to said bar rear portion by the metal strap 48^a.

In the embodiment of my invention shown in Fig. 6, said bar rear portion 26^b extends at a spaced distance from said front bar portion to only substantially the center thereof and said first-mentioned flat element 28^b comprises an integral extension of the inner end of said bar rear portion 26^b.

In the embodiment of my invention shown in Figs. 7-9, as indicated hitherto, the rear portion 41^c of the flat spring element 46^c is integrally secured to the extended rear bar portion 26^c by an integral strap portion 48^c. In this embodiment the entire necktie holder 10^c comprises a piece of metal with said rear bar portion 26^c extending substantially to the inner end of said front portion 12^c and comprises a portion of greater width underneath said front bar portion and said respective flat elements 28^c, 32^c comprise elements cut out from said widened rear bar portion 26^c and integrally joined to the side walls thereof by said integral cross bar 48^c.

In the embodiment of my invention shown in Figs. 10-12, said composite bar portions 12^d, 24^d, and 26^d are centrally cut away substantially throughout the length thereof and have a joining portion 52 ornamental as shown, at the inner end 40 of the front bar portion 12^d thereof and a joining portion 54 at the inner end of the rear portion 26^d thereof. In this embodiment the spring element 46^d is centrally cut away substantially throughout the length thereof, except at the rear portion 41^d thereof where the joining bar 56 is provided adjacent the end joining bar 54 and the metal strap 48^d projecting integrally from said bar 56 in the embodiment shown, is wrapped around the inner end bar 54 of said rear portion 26^d to rigidly secure said spring element to said bar rear portion.

In the embodiment of my invention shown in Figs. 13 and 14, said spring element 46^e comprises a piece of wire 58 doubled laterally on itself to provide the laterally spaced wire strands 60 and 62 forming the flat spring element 46^e, the respective ends 64 and 66 of said piece of wire 58 terminating underneath the respective metal strap 48^e.

In the embodiment of my invention shown in Fig. 15, the metal strap 48 is dispensed with, the rear bar portion 26^f extends substantially to the inner end of said front bar portion 12^f and said spring element 46^f, including the portions 28^f and 32^f thereof comprises an integral extension from said rear bar portion 26^f interposed between said rear bar portion 26^f and front bar portion 12^f.

The embodiment of my invention shown in Figs. 16-21 is of a general type known in the art illustrated in Patent No. 1,931,784, issued Nov. 20, 1934, to Edward S. Mix, and includes the addition of the supplemental flat spring element 32^g to such types of necktie clasps. In this embodiment, as hitherto stated, the flat element 28^g comprises the clamping portion 28^g of the clamping lever 42 pivotally mounted as at 44 on the

inner end of said bar rear portion 26^g in line with said front portion, suitable respective pivot ears 43 being provided on said respective portions 42 and 26^g to receive the pivot pin 44 therethrough for this purpose. Said clamping lever 42 is also provided with the handle portion 68 projecting outwardly therefrom beyond said pivot, the flat element 28^g secured to said bar rear portion extending resiliently inwardly and forwardly from said pivot 44 to abut the rear surface of said shirt edge adjacent the inner end of said necktie, comprising the clamping portion or arm 28^g of said clamping lever 42 projecting inwardly therefrom to abut the rear surface of said shirt edge adjacent the inner edge of said necktie. The resiliency inherently compressing said flat element 26^g against said shirt edge includes means 45 comprising the spring wrapped around said pivot pin 44 having one end abutting the rear surface of said bar rear portion 26^g and the other end abutting the front surface of said clamping lever handle portion 68 to resiliently urge the clamping surface of said clamping lever forwardly to provide the nip 30. In accordance with my invention the flat element 32^g comprises an element extending resiliently outwardly and forwardly from said clamping portion 28^g of said clamping lever 42 to abut the rear surface of said shirt edge adjacent the outer edge of said necktie and shirt edge to provide the nip 34 hitherto described. In this embodiment, the clamping surface of said clamping portion 28^g, serrated as at 72 as shown, may comprise the substantially segmental side flanges having rough convexedly curved edges as shown in said Mix patent, but preferably comprises a flat surface 74 rigidly attached to said clamping portion 28^g corrugated all the way across as at 72, each corrugation 72 being provided, if desired, with central depressions 78. As specifically shown, in the embodiment of my invention shown in Figs. 16-21, the actual clamping surface 74 of the clamping portion 28^g of said clamping lever may comprise the arm 74 of the flat spring element 46^g hitherto described in relation to the other embodiments, extending inwardly and forwardly from said rear portion 26^g on said clamping portion 28^g to abut the rear surface of said shirt edge adjacent the inner edge of said necktie and having a serrated clamping front surface 74 of the specific type hitherto described and the flat element 32^g may comprise the integral arm of such a flat spring element 46^g projecting resiliently outwardly and forwardly from said rear portion 41^g to abut the rear surface of said shirt edge adjacent the outer edge of said necktie and shirt edge as in the embodiment shown. Where a separate spring element 46^g is employed having the respective arms 74 and 32^g, it may be rigidly secured to the clamping portion or arm 28^g of said clamping lever 42 by means of the overlying strap lugs 76 to function as an integral portion thereof.

As will be apparent from the above description and as shown more particularly in Figs. 3-5 and 19-21 to attach, it is merely necessary to place the necktie holder 10 adjacent the outer end 18 of said shirt edge 16 and outer edge 20 of said necktie 14 and push it inwardly, the arm or flat element 28 resiliently pivoting from the rearwardly projecting portion 24 for this purpose to provide the nip 30, as illustrated in Fig. 4, where the necktie holder is shown in approximately midway attached position on said necktie. Then, as the necktie holder 10 further embraces said necktie, said flat portion or respective arm 32 will bend

from its point of attachment 40 to said bar rear portion 26 to provide the supplemental nip 34 to bind the outer edge of said necktie and outer edge of said underlying shirt edge against said front bar portion, the other arm or flat portion 28 providing the nip 30 to bind the inner edge of said necktie and underlying shirt edge against the inner end of said bar front portion 12. On removal of the necktie holder, it is obvious that the respective nips 34 and 30 will be successively released in reverse order. It is obvious therefore that I have provided a necktie holder which may be attached or detached without rumpling the necktie.

It is thus apparent that with this construction two independent positive nips are provided, each resiliently actuated substantially independently of each other to provide the two positive nips at each edge of the necktie to positively retain the necktie in flat position over the shirt edge, all of the embodiments of my invention shown in Figs. 1-15 functioning for attaching or detaching purposes in the manner illustrated in Figs. 3-5.

The embodiment of my invention shown in Figs. 16-21 may be attached in similar fashion, the only difference being that a supplemental resiliency in addition to that of the rearwardly extending portion 24^g is provided by the spring 45 urging the pivotally mounted clamping lever portion 28^g to abut the rear surface of said shirt edge adjacent the inner edge of said necktie, the supplemental flat element, or arm 32^g of my invention functioning in similar manner to provide a separate independent nip as in the other embodiments. The embodiment of my invention shown in Figs. 16-21, however, is slightly easier to attach as by means of pressure exerted by the thumb against the handle portion 68, the flat element 28^g may be pivoted away from said front portion to a spaced distance from below said shirt edge 16 for the more facile insertion of the necktie and underlying shirt edge between said front bar portion 12^g and spaced underlying flat element or clamping surface 28^g as illustrated in Figs. 19 and 20. When the holder 10^g is in attached position after the handle portion 68 has been released, as shown in Fig. 21, the flat clamping surface 28^g will be resiliently urged by the inherent resiliency of the rearwardly projecting portion 24^g, as in the other embodiments to abut the rear surface of said shirt edge adjacent the inner edge of said necktie, said flat surface being supplementally resiliently urged forwardly by said spring 45 functioning against said clamping lever and the independent flat element 32^g functions, just as in the other embodiments, to abut the rear surface of said shirt edge adjacent the outer edge of said necktie and shirt edge. To remove the necktie holder, in the embodiment of my invention shown in Figs. 16-21, it is obvious that it is merely necessary to again press on the handle portion 68 when the necktie holder may be more readily removed from the necktie and underlying shirt edge than may the embodiments of my invention shown in the preceding figures.

It is apparent that I have provided various species of necktie holders providing a second positive independent nip for the outer edge of the necktie while maintaining an independent positive nip for the inner edge of said necktie with the advantages portrayed above.

It is understood that my invention is not limited to the various embodiments shown and that various deviations may be made therefrom with-

out departing from the spirit and scope of the appended claims.

What I claim is:

1. A necktie holder for securing a necktie in flat formation overlying a shirt edge comprising a bar adapted to overlie said necktie and underlying shirt edge having an integral outer end bent rearwardly and inwardly to provide a rear portion extending under at least a portion of the rear face of said bar in spaced relation thereto to underlie said shirt edge, a flat element extending resiliently inwardly and forwardly from the underlying portion of said necktie holder substantially centrally of said front bar to abut the rear surface of said shirt edge adjacent the inner edge of said necktie to clamp it against said front bar and a flat element of greater length than said first flat element extending resiliently outwardly and forwardly from the shirt edge underlying portion of said necktie holder substantially centrally of said front bar to abut the rear surface of said shirt edge adjacent the outer edge of said necktie and shirt edge to clamp them against said front bar.

2. A necktie holder for securing a necktie in flat formation overlying a shirt edge comprising

a bar adapted to overlie said necktie and underlying shirt edge having an integral outer end bent rearwardly and inwardly to provide a rear portion extending under at least a portion of the rear face of said bar in spaced relation thereto to underlie said shirt edge, a flat element extending resiliently inwardly and forwardly from the underlying portion of said necktie holder substantially centrally of said front bar to abut the rear surface of said shirt edge adjacent the inner edge of said necktie to clamp it against said front bar and a flat element of greater length than said first flat element extending resiliently outwardly and forwardly from the shirt edge underlying portion of said necktie holder substantially centrally of said front bar to abut the rear surface of said shirt edge adjacent the outer edge of said necktie and shirt edge to clamp them against said front bar, said portions of said flat elements underlying the edges of said front bar being constructed of solid flat material to positively prevent any portions of said elements from passing forwardly beyond the rear edge of said front bar to crumple said necktie in use.

25

CHARLES SILVERMAN.
